COMPARTMENTED TRAY

Hugh R. Weiss, Montclair, N.J., assignor to The Pantasote Company, Passaic, N.J., a corporation of New Jersey

Filed Oct. 8, 1964, Ser. No. 82,083

Term of patent 14 years

(Cl. 548—13)

I claim:

The ornamental design for a compartmented tray, as shown.
